UNITED STATES PATENT OFFICE.

JOSHUA R. KELLY, OF WASHINGTON, DISTRICT OF COLUMBIA.

DRAFT APPLIANCE.

SPECIFICATION forming part of Letters Patent No. 764,295, dated July 5, 1904.

Application filed December 17, 1903. Serial No. 185,564. (No model.)

To all whom it may concern:

Be it known that I, JOSHUA R. KELLY, a citizen of the United States, residing at Washington, in the District of Columbia, have invented 5 new and useful Improvements in Draft Appliances, of which the following is a specification.

My invention pertains to conductors for smoke and other products of combustion; and 10 it contemplates the provision of means calculated to effectually prevent the strong draft in a high uptake or other conductor from cutting off the draft in a stove or other furnace, and this in such manner that ample draft 15 is furnished to support proper combustion in the stove or other furnace.

With the foregoing in mind the invention will be fully understood from the following description and claims when taken in connection with the accompanying drawings, forming 20 part of this specification, in which—

Figure 1 is a vertical section with my novel device applied. Fig. 2 is an enlarged perspective view of the device removed. Fig. 3 25 is an enlarged detail section taken on line 3 3 of Fig. 1. Fig. 4 is an elevation with a plurality of my novel devices applied.

Referring by letter to the said drawings, and more particularly to Figs. 1 to 3 thereof, 30 A is a conductor for smoke and other products of combustion in the form of an uptake or vertical shaft. B is a pipe connected to the conductor A, which may be properly denominated the "main" conductor and designed 35 to be connected to one or a plurality of furnaces, which may be stoves, steam-boiler furnaces, broilers, or the like, and C is my novel device for preventing the strong draft in the main conductor from interfering with ample 40 combustion in the furnace or furnaces. In the present and preferred embodiment of my invention the novel device C comprises a deflector a, arranged in the main conductor A in line with the branch pipe B and having a 45 base-flange b connected to the conductor A below the pipe B and also having side walls c, which are provided with flanges d, also

connected to the conductor A, as shown in Fig. 1, a wall e extending inwardly from the upper end of the deflector a and having upturned flanges f and also having apertures g at points intermediate of its middle and ends and an air-induction conduit h disposed at the inner side of the deflector a and riveted or otherwise directly connected thereto and 55 tapered from its lower end to its upper end, which latter extends through the top wall e, as best shown in Fig. 2.

All of the parts of my novel device are preferably formed of sheet metal, although 60 they may be obviously formed of other material in one or more pieces without involving departure from the scope of my invention.

In virtue of my novel device being arranged, as described, relative to the main conductor A and the furnace-pipe B, it will be observed that the deflector a will effectually prevent the exceedingly strong draft ordinarily present in high smoke-pipes from rushing past the pipe B at right angles thereto, and 70 thereby cutting off the draft necessary to support combustion in the furnace with which the pipe B is connected and forcing the smoke and other products of combustion back to the same. It will also be observed that in virtue 75 of the induction-conduit h being arranged, as described, relative to the deflector a and tapered from its lower to its upper end the force of the current of air will be amplified 80 en route through said conduit, so as to cause an entraining action upon the gases from the pipe B, with the result that ample draft is afforded to promote proper combustion in the furnace or furnaces connected with the pipe B and carry off the smoke and other products 85 of combustion from the same. The wall e stiffens and strengthens the free end of the deflector, with the result that liability of said end being burned away in use is reduced to a minimum. The apertures g of the said wall e permit 90 the draft to pass upwardly in sufficient volumes to aid in sweeping the smoke and other products of combustion along the main conductor.

- In the arrangement illustrated in Fig. 4 the branch pipe B', connected to the main conductor or uptake A', is connected in turn by pipes C' with a plurality of stoves or other furnaces D'. In the pipe B' and opposite the pipes C' my novel devices C are arranged after the manner illustrated by dotted lines. In other words, the said devices C are arranged substantially horizontal, and the flanges b of the deflectors a are connected to the pipe B' at the sides of the pipes C' remote from the main conductor A'. From this it follows that the devices C will prevent the strong draft through the pipe B' in the direction of the arrow from cutting off or otherwise interfering with the draft of the furnaces and at the same time will assure the supply of ample draft to properly support combustion in and carry off smoke from the furnaces.
- As before described, my novel devices may be used in connection with the smoke-conduits of furnaces of all kinds. For instance, when it is desired to connect a plurality of steam-boiler furnaces with a single uptake or smoke-pipe, as A', the devices C may be arranged, as shown in Fig. 4, with reference to pipes C', connected to the steam-boiler furnaces. When so arranged, the devices C will increase the steam-making capacity of the furnaces, notwithstanding the connection of said furnaces with the single smoke-pipe or uptake.
- Notwithstanding the material advantages of my novel devices as pointed out in the foregoing it will be observed that the same are simple and inexpensive in construction, are susceptible of being quickly and easily installed, and are calculated to withstand the high heat to which devices placed in smoke-conduits are ordinarily subjected.
- I have entered into a detail description of the construction and relative arrangement of the parts embraced in the present and preferred embodiment of my invention in order to impart a full, clear, and exact understanding of the same. I do not desire, however, to be understood as confining myself to such specific construction and relative arrangement of parts, as such changes or modifications may be made in practice as clearly fall within the scope of my invention as claimed.
- Having described my invention, what I claim, and desire to secure by Letters Patent, is—
1. The combination with a conduit having a lateral opening; of a device arranged in the conduit, in line with the opening, and comprising a deflector fixed to the conduit, at one side of the opening, and permanently inclined in a direction away from said opening, and an air-induction conduit disposed at the opposite side of the deflector, with reference to the opening.
  2. The combination with a conduit having a lateral opening; of a device arranged in the conduit, in line with the opening, and comprising a deflector fixed to the conduit, at one side of the opening, and permanently inclined in a direction away from said opening, and means at the free end of the deflector for causing an entraining action upon the gases from the opening. 65
  3. The combination with a conduit having a lateral opening; of a device arranged in the conduit, in line with the opening, and comprising a deflector connected to the conduit at one side of the opening, and inclined in a direction away from said opening and having an angular wall provided with one or more apertures, and an air-induction conduit arranged at the opposite side of the deflector, 70 with reference to the opening, and extending through said angular wall. 75
  4. The combination with a conduit having a lateral opening; of a device arranged in the conduit, in line with the opening, and comprising a deflector connected to the conduit at one side of the opening and inclined in a direction away from said opening, and having an angularly-disposed wall on its free end extending therefrom in a direction away from the opening, and provided with one or more apertures. 80 85
  5. The combination with a conduit having a lateral opening; of a device arranged in the conduit, in line with the opening, and comprising a deflector connected to the conduit at one side of the opening and inclined in a direction away from said opening, and having an angularly-disposed wall on its free end extending therefrom in a direction away from the opening and provided with one or more forwardly-extending flanges, and one or more apertures. 90 95
  6. The combination with a conduit having a lateral opening; of a device arranged in the conduit, in line with the opening, and comprising a deflector connected to the conduit at one side of the opening and inclined in a direction away from said opening, and having an angularly-disposed wall on its free end provided with one or more apertures, and an air-induction conduit disposed at the opposite side of the deflector, with reference to the opening, tapered from its receiving end to its discharge end and extending through the said wall. 100 105 110 115
  7. The combination with a conduit having a lateral opening; of a device arranged in the conduit, in line with the opening, and comprising a deflector connected to the conduit, at one side of the opening, and having at its free end an angularly-disposed wall which extends in a direction away from the opening and is provided with one or more apertures. 120

8. The combination with a conduit having a lateral opening; of a device arranged in the conduit, in line with the opening, and comprising a deflector connected to the conduit at one side of the opening, and having at its free end an angularly-disposed wall which extends in a direction away from the opening, and is provided with one or more apertures, and an air-induction conduit disposed at the opposite side of the deflector, with reference to the

lateral opening, tapered from its receiving end to its discharge end, and extending through the said wall of the deflector.

In testimony whereof I have hereunto set my hand in presence of two subscribing witnesses.
